HIS ATTORNEY

UNITED STATES PATENT OFFICE

HENRY DRUSCHEL, OF COLUMBIA, PENNSYLVANIA

AIR COMPRESSOR

Application filed December 12, 1930. Serial No. 501,916.

This invention relates to air compressors, and has particular reference to the method and means for cooling compressed air which is to be used with pneumatic tools.

5 The invention is particularly applicable to portable air compressors which are usually mounted on wheels in the form of a truck, and are conveyed from place to place where compressed air is required for operating purposes.

The portable air compressor is, therefore, used, as it were, in the field, and therefore away from cold water. From the standpoint of cooling it, therefore, presents different 15 problems than the stationary compressor.

On the portable compressor, the water is limited to the water in the engine radiator and cooling system and, consequently, there is no cold water available for cooling the air.

20 The air from the compressor is ordinarily supplied to the tools through a rubber hose and when the air is very hot, the same has a deleterious effect upon the rubber and deteriorates the same to such an extent that its 25 life is quite limited.

The present invention has for its object the method and means for cooling air compressed by a portable compressor.

A further object of the invention is to cool 30 the air to such an extent that it will not deteriorate rubber hose through which it is conveyed.

A still further object of the invention is to provide means by which the air can be cooled without any expense other than the installation of the specific means.

According to the invention, the portable compressor, which is provided with an engine having the usual water-cooling radiator and air fan with a supply tank for the compressed air, is provided with a series of air-cooling coils in the draw-off pipe from said supply tank, and said coils are mounted 40 on the side of the radiator opposite to the side on which the fan is mounted, so that the fan will draw the atmospheric air from around said coils and thus cool the compressed air in said coils.

50 The drawings illustrate an embodiment of

the invention and the views therein are as follows:

Figure 1 is a side elevational view of a portable compressor in dotted lines and with the mechanism of the invention shown in 55 full lines, and

Figure 2 is a front view similarly illustrated.

In the drawings, 6 represents the engine and 60 7 the air compressor. The crank shaft 8 of the engine is provided with the usual fan 9 which is located directly behind the usual radiator 11 which is connected to the water-cooling system of the engine 6 and 65 compressor 7.

The air compressed by the compressor 7 is delivered into a supply tank 12 which is located at any convenient point on the compressor, and in the present instance the compressor, as a whole, is mounted on wheels 13 and 70 the radiator is at the front of the device and the supply tank 12 at the rear.

Leading from the supply tank 12 is a pipe 14 which extends to a series of pipe coils 16 mounted directly in front of the face of the 75 water radiator 11 and forming an air radiator.

These coils are set two and one-half or three inches in front of the face of the radiator 11 and the final leg is provided with 80 a pair of cocks 17 which have coupling ends 18 for receiving the interfitting part of a coupler (not shown) mounted on the end of a hose which is intended to convey the compressed air to the tool at the other end of 85 said hose (not shown).

The coils are mounted in any convenient way, such as by the straps 19, and the number of pipes in each coil will depend entirely upon the temperature required.

90 Assuming that the engine and compressor are in operation, and the water circulating through the radiator 11, if the air compressed be at a temperature of 100 pounds per square inch, it has been found that the temperature 95 of the air in the tank 12 is approximately 285° F. This temperature is very hard to work with and is quite damaging to the rubber hose.

By a method and means such as that shown 100

in the drawings, it is found that the temperature of the air will be reduced to approximately 135° F. which temperature is low enough so that it will have no deteriorating effect upon the rubber hose.

5 As the fan 9 is rapidly rotated by the crank shaft 8, air from the atmosphere will be drawn through the radiator 11 which is of honey-comb construction, and by placing 10 the compressed air pipe in front of the radiator, the atmospheric air will be drawn over and around the pipe coils 16 and will thus materially reduce the temperature of 15 the air therein, while experiment has proven that there is little, if any, increase in the temperature of the water in the water-cooling system.

The location of the pipe coils in front of 20 the radiator also serves as a guard to prevent injury to the said radiator and, therefore, take the place of the usual guard which is placed on portable compressors of this type.

Of course, the compressor illustrated may 25 be modified in various ways without departing from the invention herein set forth and hereafter claimed.

The invention is hereby claimed as follows:

1. An air compressor organization comprising 30 a compressor unit, means to provide a circulation of air, a storage tank for the compressed air, a hose connection, and a conduit from the storage tank to the hose connection following a tortuous path through the 35 area of air circulation.

2. A compressor organization comprising 40 a compressor unit, a fan, means to operate the compressor and fan, a storage tank in direct communication with the compressor unit, a hose connection, and a conduit extending from the tank to the hose connection following a tortuous path adjacent to the fan.

3. A compressor organization comprising 45 a compressor unit, a storage tank in direct communication with the compressor unit, a hose connection, a conduit extending from the tank to said hose connection and provided with a tortuous area, and a fan operated in conjunction with the compressor unit tending 50 to circulate air over the said tortuous area of the conduit.

In testimony whereof I have signed my name to this specification.

HENRY DRUSCHEL.
